(57) **CLAIM**

I claim the ornamental design for a fitting for a skateboard, as shown and described.

DESCRIPTION

The invention relates to a fitting to be attached to the underside of the front and/or rear ends of a skateboard platform.

FIG. 1 is a bottom rear perspective view of a fitting for a skateboard showing my new design, the broken line showing of the front or rear end of the underside of a skateboard platform is for illustrative purposes only and forms no part of the claimed design;

FIG. 2 is a bottom rear perspective view thereof;

FIG. 3 is a rear elevational view thereof;

FIG. 4 is a front elevational view thereof;

FIG. 5 is a bottom plan view thereof;

FIG. 6 is a top plan view thereof; and,

FIG. 7 is a left end view thereof, wherein the right end view is a mirror image thereof.
